(57) **CLAIM**

The ornamental design for a front cowl of motorcycles, as shown and described.

DESCRIPTION

FIG. 1 is a front view of a front cowl of motorcycles showing my new design.

FIG. 2 is a rear view thereof.

FIG. 3 is a plan view thereof.

FIG. 4 is a bottom view thereof.

FIG. 5 is a right side view thereof.

FIG. 6 is a left side view thereof.

FIG. 7 is a perspective view of thereof as seen from the right front side.

FIG. 8 is a perspective view thereof as seen from the left front side.

FIG. 9 is a perspective view thereof as seen from the right rear side; and,

FIG. 10 is a perspective view of thereof as seen from the left rear side.

The portions represented with broken lines are not part of the claimed design.

The rear portion including the thickness and surfaces of the subject design are not part of the claimed subject matter.

The broken lines immediately adjacent the shaded areas represent the boundaries of the claimed design and form no part thereof.
